UNITED STATES PATENT OFFICE

154,807

DESIGN FOR A TOBACCO POUCH

Robert C. Richey, Springfield, Ohio

Application May 28, 1947, Serial No. 139,329

Term of patent 7 years

(Cl. D85—2)

To all whom it may concern:

Be it known that I, Robert C. Richey, a citizen of the United States, residing at Springfield, in the State of Ohio, have invented a new, original, and ornamental Design for a Tobacco Pouch, of which the following is a specification, reference being had to the accompanying drawing, forming part thereof.

In the drawings:

Fig. 1 is a side elevation of a tobacco pouch showing my new design, the tobacco receiving pocket being shown in broken lines.

Fig. 2 is a left hand end view of Fig. 1;

Fig. 3 is a top plan view of Fig. 1, the pouch portion in dotted lines fragmented for convenience of illustration; and

Fig. 4 is a bottom plan view of Fig. 1, the pouch portion fragmented for convenience of illustration.

The essential features of my design reside in the portion shown in solid lines.

I claim:

The ornamental design for a tobacco pouch, as shown and described.

ROBERT C. RICHEY.
